UNITED STATES PATENT OFFICE

WALTER A. TRATSCH, OF CHICAGO, ILLINOIS

COIN-CONTROLLED RELEASE FOR MECHANISMS

Application filed September 3, 1929. Serial No. 390,000.

This invention relates to a coin controlled release for mechanisms and has for its object to provide a construction more efficient in use than those heretofore proposed.

With these and other objects in view the invention resides in the novel details of construction and combinations of parts as will be more fully hereinafter disclosed and particularly pointed out in the claims.

Referring to the accompanying drawings forming a part of this specification in which like numerals designate like parts in all views,

Fig. 1 is a front elevational view of the completely assembled device;

Fig. 2 is a rear elevational view of the device;

Fig. 3 is a rear elevational view of the cover plate of the device;

Fig. 4 is a partial transverse sectional view taken as on the line 4—4 of Fig. 3 and looking in the direction of the arrows;

Fig. 5 is a detail view representing a slight modification of an end of the holding lever;

Fig. 6 is a front elevational view of the device with the cover plate removed;

Fig. 7 is a diagrammatic perspective view to illustrate the operation of the bar return lever and some of its associated parts;

Fig. 8 is a rear elevational view of the bracket support for the bar return lever, said view showing some of the parts associated with said lever;

Fig. 9 is a top plan view of the parts shown in Figs. 7 and 8;

Fig. 10 is a perspective view of the means, employed for moving a coin through the device;

Fig. 11 is a vertical sectional view taken as on the line 11—11 of Fig. 1 and looking in the direction of the arrows;

Fig. 12 is a vertical sectional view of the coin chute taken as on the line 12—12 of Fig. 1 and looking in the direction of the arrows;

Fig. 13 is a transverse sectional view through the coin chute taken as on the line 13—13 of Fig. 12 and looking in the direction of the arrows;

Fig. 14 is a rear elevational view of the device with some of the parts removed to more clearly illustrate the mechanism for holding and releasing the bar which is adapted to set into operation the controlled mechanism; and

Fig. 15 is a view similar to Fig. 14 showing the parts thereof in a different position.

This particular device is for the purpose of releasing a member or bar which, when released, will set into operation some mechanism, the release of said bar automatically being contingent upon the insertion in said device of a coin or disk of a predetermined size. Said device therefore serves as a lock for a mechanism and will be found particularly useful in many instances. The device is compact having, in the preferred form, dimensions of approximately five inches by six inches with an average thickness of about two inches.

Referring to the drawings, the device comprises a housing of a shape as clearly understood from Figures 1 and 11, the rear of the housing being open and the edge portions thereof provided with bosses as indicated at 1, 2 and 3 which are drilled and threaded to receive bolts or screws by means of which the device is secured in place on the mechanism to be controlled. The housing has two opposite vertical side walls 4 and 5, a top wall 6 substantially rectangularly disposed to the side walls, a bottom circular wall 7, and a front face or wall 8, the latter having a circular outwardly extending rib portion 9 within which the cover plate 10 fits.

The cover plate is centrally apertured to permit the handle 11 to pass therethrough, said handle being undetachably, but rotatably secured to the cover plate by means of an internally expanded portion 12 as illustrated in Fig. 11 so that the handle may be rotated without moving the cover plate. The shaft of the handle is provided with a rectangular pocket 13 to receive the similarly shaped head 14, of a key member 15 the opposite end 16 of which is squared to fit a similarly shaped opening in the bar return member. Thus it will be understood

that rotary motion is imparted to the bar return member from the handle 11 through the stationary cover plate 10 by means of said key.

5 Beneath the cover plate 10 is a coin disk 20 provided with five circular openings or windows 21 as shown in Fig. 6 but said disk may be provided with a lesser or greater number as desired, and is provided on its 10 front face with a circular groove 22 for a purpose that will appear hereinafter. The rear face of the coin disk is provided with a circular groove 23 of a width slightly less than the diameter of the coin intended for 15 use in the device, there being provided radial openings or passageways 24 into the groove 23 at stated intervals, as many passageways as there are windows 21 and each passageway constituting a coin pocket adapted to 20 come into registry with the coin chute 25 presently to be described. The coin disk 20 rests upon the circular shoulder 26 formed in the front wall 8 of the housing, and is kept from displacement therefrom by a nut 27 screwed upon the front end of the sleeve 25 of a star wheel disposed behind the front wall, said sleeve extending through said wall and said disk and having a flat 28 formed on the side thereof which is engaged by a similar flat formed in the aperture of 30 the coin disk and through which said sleeve extends, as a result of which the coin disk and star wheel are interlocked and will therefore rotate together.

35 The cover plate 10 has rigidly secured thereto two diametral pins 29 and 30 each provided with a head and adapted to be passed through a bayonet slot such as 31 formed in the front wall of the housing.

40 When the cover plate with its pins is inserted in place and given a slight rotary movement the heads of said pins will engage the underside of the narrow portion of the bayonet slots which are made of sufficient length to cause a bore 32 on the innermost face of the cover plate to register with a locking screw 33 which is operated from the inside of the housing, see Figs. 3, 6, and 11, to enter the bore and thus secure the 45 cover plate against unauthorized removal.

50 The coin chute is peculiarly formed. That is to say, in the front wall of the housing there is formed a slotway 35 which is adapted to receive a removable member 36 routed on its innermost side to provide a groove of a dimension to slidably receive the coin intended for use with this device, all as will be readily understood from Figs. 6, 12 and 13, there being provided the usual 55 circular opening 37 through which the coin is inserted by the operator. The upper end of the member 36 is provided with a head 38 having a downwardly extending flange 39, spaced parallel to the main body portion 60 of said member, said flange adapted to enter

a suitable opening formed in the upper extremity of the housing and to engage the inner surface of the front wall 8 thereof, so that when said member is in place the flange will lock the top end thereof against displacement from the groove 35. The lower end of the member 36 on its front face is formed with an outstanding rib portion which constitutes part and continuation of the rib 9 formed on the front face of the 70 housing. The said rib 9 as well as the member 36 is provided with an inwardly extending groove 40 adapted to be engaged by a circular rib 41 formed on the rear side of the cover plate 10 for the purpose of locking 75 said member against a longitudinal sliding movement in the groove 35 and the withdrawal of said member from the device when the cover plate is in assembled position. The reason for having the member 36 80 separately formed and removable from the device is to enable an authorized person to remove said member for the purpose of clearing the coin chute should the latter become obstructed.

85 The sleeve 50 has rigidly secured thereto at one end a star wheel 51, both being centrally apertured to receive therethrough the key 15, the sleeve having a bearing and supporting fit in a central opening in the front 90 plate of the housing, see Figs. 9, and 11, so that the star wheel will not rotate except with the sleeve and coin disk 20 by virtue of the flat 28 as above described. As best seen in Figs. 14 and 15 each point of the star 95 wheel is provided with a flat surface 52 to engage a pin 53 carried by a lever 54 pivoted as at 55 to the front plate of the device, said lever being of sufficient length so that its lower end will rest against a boss 56 formed 100 on said front plate. This lever is set slightly to one side of the vertical central plane of the sleeve 50 so that when the star wheel is attempted to be moved in a clock-wise 105 direction as seen in Fig. 14, the surface 52 of one of the points of said wheel will abut the pin 53 and prevent further rotational movement of the wheel in this direction.

110 Between each pair of adjacent points of the star wheel 50 is a circularly formed 115 pocket 57 to receive successively a roller 58 carried at the lower end of an unlatching lever 59 pivoted to the front plate as at 60 120 so that, as the star wheel is rotated in a counter clock-wise direction as seen in Fig. 14, said roller will be forced out of a pocket 125 of the star wheel by the teeth thereof and thus cause an oscillation of said lever. Said lever is extended beyond its pivot 60 and provided with a head 61 upon which is secured a pin 62 adapted to engage a cam 130 surface 63 disposed at the end of a holding lever 64 pivoted as at 65 to the front plate 135 of the device and having an end beyond said 130

5 pivot in which there is formed a notch 66 engageable by the tooth 67 of a detent 68 pivoted as at 69 to the housing, said tooth 67 being under the tension of a spring to cause engagement thereof with the end of the holding lever.

10 From Figures 14 and 15 it will therefore be understood that when the star wheel 51 is rotated in a counter clock-wise direction as indicated by the arrow in said figures, the lever 59 in oscillating will cause its pin 62 to engage the cam surface 63 and ride thereover, in this movement causing an oscillation of the holding lever 64, the parts 15 being illustrated in Fig. 15 at a time just before this holding lever has accomplished its purpose, which will be presently described. The head 61 of the unlatching lever 59 has a lateral extension 75 the under edge 20 portion of which forms a cam surface 76. The unlatching lever is controlled as by a spring 77 to maintain engagement of the roller 58 with the star wheel but should, for any reason, said lever be left in such a position 25 as shown in dot and dash lines in Fig. 15 a dog 78 pivoted as at 79 to the front plate and controlled as by the spring 80 will have its end 81 struck and moved to cause its other end 82 to engage the cam surface 30 76 of said lever and cause an oscillation thereof which will again place the roller 58 within a pocket of the star wheel, or in other words, said dog will correctly position the lever and star wheel for subsequent operations. A light leaf spring 83 is carried by the lever 54 and disposed between it and one side of the unlatching lever 59, see Fig. 35 14.

40 In Fig. 5 there is shown a slight modification of construction wherein it will be seen that the holding lever 64 is replaced by a lever 84 one end of which is formed exactly like the corresponding end of the lever 64, but whose other end is formed with 45 a notch 85 of much larger dimension and greater angularity than the notch 66. Further the lever 84 is formed with a curved edge portion constituting a cam surface 86 adjacent the notch 85 which is adapted to 50 be engaged by an upper corner of the operating bar presently to be described so that, as the bar moves over said cam surface, a rocking of the lever 84 will result about its pivot 65 and cause the lever to be moved from its dotted line position into its solid line position as shown in Fig. 5 in which latter position it is held by the tooth of a detent 87 somewhat similar to the detent 68. The disadvantage of this action is that 55 the full force of the moving operating bar is desired and the frictional engagement of it with the cam surface 86 will have a tendency to diminish this force. On the other hand, the construction shown in Figs. 2 and 60 14 provides an unobstructed movement of

the operating bar so that when it has assumed a position as shown in Fig. 2, it will strike an anvil 88 formed on the side of the detent 68 and cause disengagement of the latter with the holding lever 64. The upper side of the tooth 67 of the detent is angularly formed so that when the lever 64 is returned to the position it is shown in, it will ride over the end of the detent, all as will be readily understood.

70 Referring now to Figs. 7, 8, 9, 10 and 11 it will be seen that the key 15 extends through the star wheel 51 and that the squared end of said key is adapted to engage a square opening in the center of what may be termed the bar return lever. The front plate 8 of the housing is provided with an arcuate slot 89 within which is adapted to be moved a finger 90 of a length to extend all the way through said slot and to engage the edge of a coin of the predetermined size which has been inserted to unlock the mechanism and which is resting in the groove 23 of the coin disk. Due to the fact that said groove is of a width 80 slightly less than the diameter of the predetermined coin, as hereinbefore stated, said coin will not be moved through the groove 23 by said finger but it will be caused to 85 abut the corner, such as 91, formed by said groove and the radial passageway 24 associated therewith and through which said coin gained said groove, as a result of which the continued movement of the finger 90 will cause both said coin and coin disk to 90 move simultaneously in locked relation. This finger is freely pivoted as at 92 to one end of the bar return lever 93 in one side of whose pivotal center is a squared opening 94 to receive the end 16 of the key 15. 95 The other side of the bar return lever is centrally provided with a circular boss adapted to pass through and rotatably engage a circular opening in a bracket member 95 supported in the housing by bolts passing through the holes 96 and 97 formed in the ends of said bracket, said bar return lever 100 being disposed between said bracket member and the star wheel 51.

105 The portion of the boss extending beyond the bracket member is threaded and engaged by a plate 98 having on its inner face a pin 103 to which is secured one end of a strong flat coil spring 99, the other end of which is secured as at 100 to the bracket 95. The 110 purpose of this spring therefore will be seen to return the bar return lever 93 to a position where the finger 90 will engage the next inserted coin. This position is reached when a pin 101 carried by said lever comes to 115 rest in a pocket 102 formed on the upper side of the bracket member, said pin being adjacent the end of the bar return lever carrying said finger. A usual and well known full-stroke compelling mechanism is 120 125 130

employed with relation to the bar return lever comprising the rack 103 mounted on the housing and engaged by the spring controlled detent 104 carried at the opposite end of said lever. The coin finger 90 has a depending stop 105 adapted to engage a shoulder 106 formed on the end of the bar return lever for limiting movement in one direction of said finger, which is controlled by a spring 107 carried by the lever 93.

10 The operating bar is represented in the drawing by the numeral 110 and is pivoted at its lower end as at 111 to the housing, there being provided a heavy coil spring 112 to keep the bar under tension. The upper end of the bar is provided with a turned-over end 113 the edge of which is adapted to rest against a shoulder 114 formed at one extremity of the cam surface 63 of the holding lever 64 so that when the cam end of said lever is moved upwardly as indicated by Figs. 14 and 15 the end of the bar 110 will be released whereby the spring 112 will cause said bar to fly to the right, as seen in said figures, either striking or otherwise moving a member to start the actuation of the mechanism which is to be controlled by this device. The parts struck or moved are not shown in the drawings for the sake of clearness and because they may be varied in design and construction, and since the invention solely resides in the control of the movement of the bar 110.

15 The means for resetting the bar 110 is 35 the pin 101 carried by the bar return lever 93. In other words, when the key 15 is rotated it will oscillate said lever causing the pin 101 to engage the side of the bar 110 and oscillate said bar about its pivot, 40 moving it from the position shown in Fig. 2 to the position shown in Fig. 14. During this movement the end 113 of said bar will ride under the lower edge of the holding lever 64 causing the latter to oscillate about its pivot until the end of said bar reaches 45 the end of said lever, at which time said end will snap into the angle formed by the cam surface 63 and the shoulder 114 of said lever.

50 As an additional lock for the operating bar 110 there is provided a C shaped releasing lever 115, pivoted to the housing as at 116 the lower extremity 117 of said lever lying in the vertical plane of and adapted 55 to be struck by the bar return lever 93 when the latter is returned under the tension of its control spring 99. In other words, and with particular reference to Figs. 2 and 7 it will be seen that when the bar return 60 lever reaches the position shown in Fig. 2 one corner thereof 118 will engage the end 117 of the releasing lever and oscillate it in a direction to cause its opposite end 119 to release the end 113 of the bar 110. That 65 is to say, a spring 120, see Fig. 2, normally

holds the end 119 of the releasing lever in latching position with respect to the operating bar 110, but when said lever is operating as just described, the operating bar will be released and it will fly under spring 70 tension from the position shown in Fig. 14 to the position shown in Fig. 2. When the bar is returned it will strike the oblique cam surface of the end 119 of the releasing lever and oscillate the latter to permit passage 75 of said bar past said end, and the levers 64 and 115 are so dimensioned and placed that the end 113 of the bar will simultaneously pass the ends of said levers and thus 80 permit both levers to lock said end at the same time. One end of spring 120 is attached to the releasing lever 115 and its other end is secured to the detent 68, thereby keeping both under common tension.

85 The front wall 8 of the casing is provided with an opening 123 best shown in Fig. 14 through which the coins may drop from the coin disk 20 into a suitable space within the housing or into a coin box adapted to hold the coins until they are collected. The 90 lower edge of this opening is bevelled as indicated at 124 to assist in the direction of the coins into said space. The front cover plate 10 has mounted upon its rear face a leaf spring 125 having secured at its free 95 end a pin 126 which is adapted to be moved in a direction away from said plate for the purpose of tilting a coin, such as shown in Fig. 4 at 127, from its position within the 100 coin disk, when said coin has travelled around to a position opposite the opening 123 in the front wall of the housing. The means for moving said pin comprises a finger 128 having a bevelled edge, said finger being an extension on the member 129 105 secured to the internal flange 12 of the stud of the handle 11.

110 In other words and with particular reference to Fig. 3 it will be understood that as the handle is rotated the member 129 110 will move therewith over the inner surface of the cover plate 10 from a position such as shown in full lines to the dotted line position, at which time the finger 128 will ride under the projecting pin 126, springing 115 it away from said plate. The coin, such as 127 (see Fig. 4), is thus positively ejected from its position in the coin disk 20 and falls by gravity, as indicated, into the space intended to receive it. The inner 120 surface of the bottom wall of the housing may be upwardly inclined as shown in Fig. 4 to prevent collected coins from interfering with the movement of the coin disk 20. The circular groove 22 provided in the front 125 face of said coin disk is for the purpose of providing a clearance between said disk and the pin 126 when the latter is in its inoperative position, and the peripheral enlargement of each window 21 in the coin 130

disk is provided to allow clearance for the leaf spring 125.

The operation of this device is as follows: When a coin of the predetermined size has been inserted in the coin chute 25, it will drop by gravity into a pocket formed by the slot 23 of the coin disk 20 and rest against one of the corners between said slotway and the radial passage 24 through which the coin has just passed. The operator then turns the handle 11 in a clock-wise direction as seen in Fig. 1 which causes the bar returning lever 93 to move about its pivot whereupon the finger 90, carried at the end of said lever, will enter the arcuate slot 89, engage an edge of the inserted coin and, through said coin, cause the coin disk 20 to be rotated. The star wheel 51, being locked to said disk by means of the flat 28, will likewise be rotated and during this movement a tooth of the star wheel, contacting with the roller 58, will cause an oscillation of the lever 59 about its pivot 60 with consequent movement of the pin 62 into operative engagement with the cam surface 63 of the holding lever 64 causing the latter to move out of a latching relation with respect to the operating bar 110.

During this movement of the several parts, the pin 101 carried by the lever 93 will be arcually moved and, if the operating bar 110 is in the position shown in Fig. 2, said pin will move said bar about its pivot 111 to the position shown in Fig. 14, in this movement creating a greater tension upon the spring 112 controlling said bar. When the handle 11 has been turned clock-wise to the limit of its movement, the upper end of the operating bar 110 will have passed beyond and become latched by the upper end of the C shaped releasing lever 115. During the turning of the handle 11 the spring 99 will have placed the bar returning lever 93 under tension sufficient to cause a natural return movement of the handle and said lever in a counter clockwise direction during which movement the upper end corner 118 of said lever will come up and strike the lower end 117 of the releasing lever, the impact being sufficient to oscillate said last mentioned lever and cause its upper end to release the end 113 of the operating bar 110. When thus released said bar 110 will fly from the position shown in Fig. 14 to the position shown in Fig. 2, striking in its movement the desired portion of the mechanism being controlled by this device, to set said mechanism into operation.

At the end of these operations the inserted coin will have passed to a position indicated at 130 in Fig. 6 where it is visible not only through a window 21 in the coin disk 20 but also visible through a window 131 in the cover plate 10. The mechanism being controlled may be provided with any suitable

means for stopping the operation thereof at a predetermined time, such as at the end of a rendition in the case of a player piano, but inasmuch as this forms no part of the device herein described it will be sufficient to state that said device will not be actuated again until the mechanism is desired to be put in operation.

When the next coin is inserted in the coin chute 25 it will pass to a similar position in the coin disk 20 as above described and when the handle 11 is again rotated in a clock-wise direction the same movements as above described will take place, the cam end of the holding lever being raised by the pin 62 and the operating bar passing beneath the releasing lever 115. The return of the handle 11 and its associated lever 93 will unlatch the releasing lever 115 and cause said operating bar to set in operation the controlled mechanism. The coin just inserted will then have passed to the position 130 and the previously inserted coin will have passed to the position 132, see Fig. 6, where it is visible as through the window 133 in the cover plate 10.

The same operations are repeated when a third coin has been inserted which passes to the position 130, the two previously inserted coins passing to the positions 134 and 132 respectively, the first inserted coin now being visible through the window 135 of the cover plate 10. When the next coin is inserted, however, and the handle turned as before described, the first coin inserted will be moved by the coin disk around to a position to be ejected therefrom by the coin clearing pin 126, each of the previously inserted coins passing a step forward as will be understood from the foregoing.

It often occurs that a machine adapted to be coin controlled is subjected to actuation or attempted actuation by an operator without the insertion of a coin, with the expectancy of getting something for nothing, and therefore devices of this and similar character must be so constructed as not to allow the mechanism to be unlocked unless a coin of predetermined value and size is used. Therefore, when one turns the handle 11 without inserting a coin as described, the handle offers no resistance but, since there is no coin against which the finger 90 can contact, there will be no simultaneous movement of the star wheel and coin disk with the handle, and therefore there will be no movement of the lever 59. Consequently the lever 64 remains in the position shown in Fig. 2.

However, since the bar return lever 93 is simultaneously oscillated by movement of the handle, the releasing lever 115 and the operating bar 110 will be moved as just above described but in the movement of the latter its upper end will ride under the

curved lower edge of the lever 64, which is so shaped as to permit said lever to be rocked about its pivot. When the operating bar has substantially reached the limit of its movement to the left as seen in Fig. 2 both levers 59 and 64 will be moved under spring action to latch the upper end of said bar, during which movement the finger 90 will likewise have engaged the dog 78, the upper end of which causes a placement of the lever 59 with its roller 58 within a pocket between two adjacent teeth of the star wheel. The tension of the spring 99 will, as usual, cause a return of the handle 11 to its original position during which movement the releasing lever 115 will be rocked so that its upper end will pass out of latching engagement with the operating bar, but the latter will not be permitted to fly to the position shown in Fig. 2 since the shoulder 114 of the lever 64 will hold it. In other words it requires a coin in the coin disk, and against which the finger 90 contacts, to cause a rotary movement of the star wheel which in turn controls the releasing of the lever 64 through the intermediate lever 59.

The handle 11 can be operated as many times as desired without the insertion of a coin but, regardless of how many times it is operated, the operating bar will remain latched under spring tension by the holding lever 64. When, however, the next coin is inserted for legitimate operation of this device, the star wheel will be permitted to rotate and, through the lever 59, cause a release of the lever 64, whereupon the operating bar will be freed when the handle returns to its position of rest and rocks the releasing lever 115.

It is obvious that those skilled in the art may vary the details of construction and arrangements of parts without departing from the spirit of this invention, and therefore it is not desired to be limited to the foregoing disclosure, except as may be demanded by the claims.

What is claimed is:

1. In a coin controlled release for mechanisms the combination of an operating bar; holding means for said bar; coin-controlled unlatching means for said holding means; operating bar releasing means; and means for moving said releasing means as well as placing said bar under tension.
2. In a coin controlled release for mechanisms the combination of a pivoted operating bar; holding means comprising a pivoted member for said bar; coin controlled unlatching means for said holding means; operating bar releasing means; and means for moving said releasing means as well as placing said bar under tension.
3. In a coin controlled release for mechanisms the combination of an operating bar; holding means for said bar; cam operating

coin controlled unlatching means for said holding means; operating bar releasing means; and means for moving said releasing means as well as placing said bar under tension.

4. In a coin controlled release for mechanisms the combination of an operating bar; holding means for said bar; coin controlled unlatching means for said holding means; operating bar releasing means comprising a pivoted member under spring tension; and means for moving said releasing means as well as placing said bar under tension.

5. In a coin controlled release for mechanisms the combination of an operating bar; holding means for said bar including a detent engageable with said means; coin controlled unlatching means for said holding means; operating bar releasing means under common tension with said detent; and means for moving said releasing means as well as placing said bar under tension.

6. In a coin controlled release for mechanisms the combination of an operating bar; holding means for said bar; coin controlled unlatching means for said holding means; operating bar releasing means; and common means for moving said releasing means when operated in one direction and placing said bar under tension when operated in another direction.

7. In a coin controlled release for mechanisms the combination of an operating bar; holding means for said bar; coin controlled unlatching means for said holding means; operating bar releasing means; means for moving said releasing means as well as placing said bar under tension; and means controlled by an inserted coin for operating the unlatching means.

8. In a coin controlled release for mechanisms including an operating bar under tension the combination of a coin receiving disk; operating bar releasing means; and means for actuating said releasing means including a star wheel carried by said disk; and a member engageable with a coin in said disk for moving the latter.

9. In a coin controlled release for mechanisms including an operating bar and a handle for placing said bar under tension whenever said handle is actuated the combination of a freely mounted member provided with pockets to receive inserted coins; operating bar releasing means; means carried by said member for actuating said releasing means; means movable with said handle and engageable with a coin in one of said pockets for actuating said member; and means actuated by said last mentioned means to position said member for receiving coins in said pockets upon a complete movement of said handle.

10. In a coin controlled release for mech-

anisms including an operating bar and a handle for placing said bar under tension whenever said handle is actuated the combination of a freely mounted member provided with pockets to receive inserted coins; operating bar releasing means; means carried by said member for actuating said releasing means; means movable with said handle and engageable with a coin in one of said pockets for actuating said member; and means cooperating with said releasing means and actuated by said last mentioned means to position said member for receiving coins in said pockets upon a complete movement of said handle.
